UNITED STATES PATENT OFFICE

REGINALD P. REARDEN, OF WARRENVILLE, SOUTH CAROLINA

LOOM-TAPE SELVAGE-MOTION HANGER AND BEARING

Application filed October 31, 1929. Serial No. 403,845.

This invention relates to a loom tape selvage motion hanger and bearing and has for one of its objects to provide, in a manner as hereinafter set forth, a device of this character which will be simple in construction, strong, durable, efficient in its use and which may be manufactured at low cost.

Another important object of the invention is to provide, in a manner as herein-after set forth, a loom tape selvage motion hanger and bearing which may be expeditiously and adjustably mounted on either the right or left side of the loom for use.

Other objects and advantages of the invention will become apparent from a study of the following specification, taken in connection with the accompanying drawings, wherein like characters of reference designate corresponding parts throughout the several views, and wherein:

Figure 1 is a view in front elevation of the invention.

Figure 2 is a view in side elevation thereof.

Figure 3 is a view in transverse section showing the means for mounting the stand on the hanger.

Figure 4 is a sectional view taken through the pulley.

Referring to the drawings in detail, the reference character 1 designates a portion of the arch of the loom to which is bolted a downwardly and forwardly extending hanger 2 through the medium of a foot portion 3 which is engaged against said arch and a threaded securing element 4. The free end of the hanger 2 has formed integrally thereon an elongated transversely extending cylindrical eye 5 through the forward wall of which is threaded a set screw 6.

The reference character 7 designates generally the adjustable stand which comprises a substantially U-shaped bracket including a pair of parallel spaced vertical arms 8 and a connecting portion 9. An elongated shaft 10 extends laterally from the lower end of the bracket 7 at one side thereof and is adapted to be disposed through the eye 5 of the hanger 2. The shaft 10 is adapted

for both rotary and longitudinal adjustment in the eye 5 and is secured in adjusted position through the medium of the set screw 6. The free ends of the arms 8 of the bracket are bifurcated, as at 11, for the purpose of supporting the pulley 12 therebetween.

The pulley 12 comprises an annulus 13 provided, on the marginal portion of its periphery, with circumferentially extending guide ribs 14 and said annulus 13 is further provided with a pair of rings 15 which are mounted on its inner periphery and at its opposite ends. Bearing rings 16 are mounted in the rings 15 and mounted for rotation in the bearing rings 16 are the hub portions 17 from which extend the trunnions 18. Ball bearings 19 are disposed between the hubs 17 and the bearing rings 16 and the trunnions 18 are provided with longitudinal bores 20 which communicate with bores 21 in the hub portions for conducting a lubricant to the ball bearings. The open ends of the bores 20 are closed through the medium of threaded plugs 22. The trunnions 18 are adapted to be disposed in the bifurcated ends of the arms 8 of the bracket 7.

A flexible leather strap 23 is trained over the pulley 12 and is secured to the selvage tape harness 24 through the medium of an inverted substantially U-shaped connecting element 25.

It will thus be seen that I have provided a loom tape selvage motion hanger and bearing wherein the stand may be expeditiously adjusted to any desired position with respect to the hanger by simply loosening the set screw 6 and shifting the shaft 10 to the desired position in the eye 5. It will also be seen that the stand is reversible and can, therefore, be mounted for use on either side of the loom. The pulley construction and mounting is such that the same can be removed by simply lifting it out of the arms 8 for any desired purpose, such as lubricating the same, but it is to be understood that the same may be lubricated while in position on the stand by simply removing the threaded slotted plugs 22.

It is believed that the many advantages

of a device constructed in accordance with this invention will be readily understood, and although the preferred embodiment of the invention is as illustrated and described, it is to be understood that changes in the details of construction may be had which will fall within the scope of the invention as claimed.

What is claimed is:—

- 10 A loom tape selvage motion hanger and bearing of the character described comprising an inclined hanger, a foot portion formed integrally on one end of the hanger and extending at an acute angle downwardly with respect thereto and adapted for engagement with the arch of the loom, means for anchoring the foot portion to the arch, an elongated transversely extending cylindrical eye on the free end of the hanger, a
- 15 pulley stand mounted for rotary and longitudinal adjustment on the hanger and comprising a substantially U-shaped bracket having spaced parallel arms and a connecting portion at one end thereof, the free ends of said arm being bifurcated, an elongated shaft extending laterally from the bracket at the connected ends thereof and extending for rotary and longitudinal adjustment through the eye, means for securing the
- 20 shaft in adjusted position in the eye and a pulley mounted for rotation on the bifurcated ends of the arms.

In testimony whereof I affix my signature.
REGINALD P. REARDEN.
